UNITED STATES PATENT OFFICE.

JOHN BROATCH, OF VANCOUVER, BRITISH COLUMBIA, CANADA.

ADVERTISING-MACHINE.

1,371,467.

Specification of Letters Patent. Patented Mar. 15, 1921

Application filed July 15, 1920. Serial No. 396,357.

To all whom it may concern:

Be it known that I, JOHN BROATCH, a subject of the King of Great Britain, and a resident of the city of Vancouver, in the Province of British Columbia, Canada, have invented certain new and useful Improvements in Advertising-Machines, of which the following is a specification.

My invention relates to improvements in advertising machines, and the object of my invention is to provide a simply constructed, practical and efficient means whereby advertising matter may be displayed mechanically and in a highly novel and attractive manner.

I attain this object by the construction illustrated in the accompanying drawings in which—

Figure 1 is a front view of the machine. Fig. 2 is an end view with one side removed.

Fig. 3 is a sectional plan view taken on line 3—3 of Fig. 1.

Similar figures of reference indicate similar parts throughout the several views.

1 indicates the casing of the machine within which are inclosed the several parts, and which is provided with a display opening 2, the edge of which may be flared outwardly as at 3, if desired. Positioned within the casing behind the opening 2 and of greater area than the same are advertising plates 4 on which the advertising matter is printed, there being seven such plates shown in the device illustrated in Fig. 2, although there may be any other desired number, and these plates are arranged one behind the other, the innermost plate being supported by vertical supporting members 5, formed preferably of angle iron, which are inclined slightly backwardly, there being one such member adjacent the ends of the sign plates. The upper ends of the members 5 are bent backwardly to form an inclined table or chute 6 on which the respective plates fall when elevated, as hereinafter described. Each plate 4 is provided at midlength with a toothed rack 7 with the upper end of which a rotatably mounted gear 8 is adapted to normally engage, and which gear is operated by a gear 9 secured to the shaft 10 on which gear 8 is mounted, the gear 9 being itself driven by a gear 11 secured to a suitably supported rotatable shaft 12 operated by a motor 13 with which it is con-

nected by any approved driving means such as sprockets 14 and 15 and chain 16.

Positioned directly above the plate elevating gear 8 is a gear 17 secured to a shaft 18. Gear 17 is driven by a gear 19 carried on the shaft 18 and meshing with the gear 11. Arranged in front of the supports 5 between the gears 8 and 19 is a guide member 20. Between this member 20 and the vertical members 5, the plates 4 are guided in their upward movement.

21 and 22 indicate sheaves rotatably mounted in the upper part of the casing 1 around which are passed cables 23 and 24 to the front ends of which is secured a curtain 25 which passes over a roller 39 and the lower edge of which is provided with an inwardly projecting ledge as indicated at 26 the under surface of which is beveled outwardly as at 27 while to the opposite ends 75 of the cables are secured counterweights 28 and 29, the weight of which is such as will practically balance the curtain and maintain it with the ledge 26 just slightly above the upper edge of the opening 2.

The lower end of the counterweight 28 is adapted to contact when in its lower position with a depressible electrical terminal 30 carried by a stationary support 31 within which is secured a stationary terminal 32, 85 wires 33 and 34 of a suitable electrical circuit used for illuminating the machine being connected respectively to the terminals 30 and 32. The terminal 30 is resiliently supported by a spring 35 so as to be raised 90 to its normal position to break the circuit when the counterweight rises.

36 indicates a stop member having an inclined face 37 against which the beveled surface 27 of the ledge contacts when the 95 curtain reaches its lowest position and 38 indicates an opening in the front of wall of the casing 1 opposite the stop 36.

The manner in which the machine operates may be described briefly as follows: 100 On the motor being started the gears 8 and 17 are rotated so that the back advertising plate is raised, being elevated until it overbalances and falls backwardly on the chute 6 when it shoots forwardly of its own accord 105 so that its lower edge falls on to the ledge 26 of the curtain. The weight of the plate then causes the curtain to drop and as soon as it commences to travel downwardly the electrical circuit is broken by the separa- 110

tion of the terminal 30 from terminal 32 due to the rising of the counterweight so that the machine is in darkness while the curtain is dropping. On reaching the end 5 of its travel the beveled surface 27 of the curtain ledge 26 contacts with the inclined face 37 of the stop 36 so that the ledge of the curtain passes into the opening 38 tilting it and allowing the plate to fall free, 10 whereupon the curtain is then raised again by the counterweights, the illumination of the machine being again switched on when the counterweight 28 causes the terminal contact to be again made. The operation 15 just described is continuous as long as the motor is in operation, each back plate being taken and moved mechanically to the front and as the changing of the plates takes place in the dark without any mechanism being 20 visible the machine possesses great novelty and is highly attractive.

What I claim as my invention is:—

1. An advertising machine comprising a casing having a display opening, a plurality 25 of advertising cards stacked directly behind said opening with the front card exposed through the opening, and means for elevating the rearmost card of the stack and then guiding it forwardly and down- 30 wardly to an exposed position in advance of the remaining cards and opposite said opening.

2. An advertising machine comprising a casing having a display aperture, a plurality 35 of advertising plates arranged one behind the other behind said aperture, supports for said plates adapted to maintain them slightly inclined backwardly, a forwardly and downwardly inclined chute at 40 the upper end of said supports, means for raising said plates one at a time to a height at which they overbalance and fall on said chute, and a curtain hung above said aperture having a projecting ledge at its lower 45 edge adapted to receive the lower edge of a plate as it drops from the chute, said curtain being adapted to be then lowered by the weight of the said plate.

3. An advertising machine comprising a 50 casing having a display aperture, a plurality of advertising plates arranged one behind the other behind said aperture, supports for said plates adapted to maintain them slightly inclined backwardly, a forwardly and downwardly inclined chute at 55 the upper end of said supports, means for raising said plates one at a time to a height at which they overbalance and fall on said chute, a curtain hung above said aperture 60 having a projecting ledge at its lower edge adapted to receive the lower edge of a plate as it drops from the chute, said curtain being adapted to be then lowered by the weight of the said plate, and means for free- 65 ing the plate from the curtain ledge when

the curtain reaches the termination of its downward travel.

4. An advertising machine comprising a casing having a display aperture, a plurality of advertising plates arranged one behind the other behind said aperture, supports for said plates adapted to maintain them slightly inclined backwardly, a forwardly and downwardly inclined chute at 70 the upper end of said supports, means for raising said plates one at a time to a height at which they overbalance and fall on said chute, a curtain hung above said aperture having a projecting ledge at its lower edge adapted to receive the lower edge of a plate 75 as it drops from the chute, said curtain being adapted to be then lowered by the weight of the said plate, means for freeing the plate from the curtain ledge when the curtain reaches the termination of its down- 80 ward travel, and means for then raising the curtain to its normal position.

5. An advertising machine comprising a casing having a display aperture, a plurality of advertising plates arranged one behind the other behind said aperture, supports for said plates adapted to maintain them slightly inclined backwardly, a forwardly and downwardly inclined chute at 90 the upper end of said supports, means of raising said plates one at a time to a height at which they will overbalance and fall on said chute, a curtain hung above said aperture having a projecting ledge at its lower edge adapted to receive the lower edge of a 95 plate as it drops from the chute, said curtain being adapted to be then lowered by the weight of the said plate, means for freeing the plate from the curtain at the termina- 100 tion of its downward travel, counterweights for raising said curtain when the plate is freed therefrom, and an illuminating means adapted to be set in operation by one of said counterweights coincidently with its return to normal position.

6. An advertising machine comprising a casing having a display opening, a normally inoperative closure for said opening, a plurality of cards adapted to be successively moved to an exposed position opposite said 115 opening, and means for utilizing the weight of said cards to move the closure member across the opening during the period of changing the cards.

7. An advertising machine comprising a 120 casing having a display aperture, a normally counter-balanced inoperative closure for said aperture, a plurality of cards adapted to be successively moved to an exposed position opposite the aperture, and 125 means for utilizing the weight of said cards to move the closure across the opening during the period of changing the cards.

8. An advertising machine comprising a 130 casing having a display aperture, a normally

inoperative curtain for closing said aperture, a plurality of cards stacked within the casing, means for successively moving said cards to an exposed position opposite said aperture, and means for utilizing the weight of each card in its movement to exposed position to draw the curtain across the aperture.

9. An advertising machine comprising a casing having a display aperture, a normally inoperative curtain for closing said aperture, a plurality of cards stacked within the casing, means for successively moving said cards to an exposed position opposite said aperture, means for utilizing the weight of each card as it is moved to exposed position to draw the curtain across the aperture, and means for releasing the

curtain as the card reaches its limit of movement.

10. An advertising machine comprising a casing having a display aperture, a movable closure for said aperture normally maintained in an operative position, means for illuminating said casing controlled by the movement of said closure, a plurality of display cards, means for successively displaying said cards opposite said opening, and means for utilizing the weight of each card as it moves to an exposed position opposite the opening to move said closure across the aperture and to simultaneously shut off the illuminating means.

Signed at Vancouver, B. C., Canada, this 2nd day of July, 1920.

JOHN BROATCH.
